UNITED STATES PATENT OFFICE.

FREDERICK WILLIAM ROMERIL, OF RAYMOND, ALBERTA, CANADA.

AUXILIARY AIR INLET.

Application filed October 22, 1921. Serial No. 509,588.

To all whom it may concern:

Be it known that I, FREDERICK WILLIAM ROMERIL, of the village of Raymond, in the Province of Alberta, Canada, have invented 5 certain new and useful Improvements in Auxiliary Air Inlets, of which the following is the specification.

My invention relates to improvements in gasoline savers for internal combustion 10 engines, particularly applicable to automobile engines and the object of the invention is to devise a simple and effective gasoline saver that will be controlled by the spark lever.

15 My invention consists of a gasoline saver constructed and arranged substantially as hereinafter more particularly described and illustrated in the accompanying drawing in which:

20 Fig. 1 represents a side elevation of the manifold side of an engine showing my device applied thereto.

Fig. 2 is a plan view showing the valve of my device connected to the spark rod.

25 Fig. 3 is a cross sectional view of the valve.

Fig. 4 is an elevational view partly in section of the cone mixer, and

30 Fig. 5 is an elevation at right angles to Figure 4 partly in section.

Like characters of reference indicate corresponding parts in the different views.

1 is the intake manifold of the engine. 2 is the carburetor. 3 is the exhaust manifold. 35 4 is a stove adapted to be situated on the exhaust manifold. 5 is the valve casing suitably secured to the stove 4 by means of the hollow screw plug 6, said valve casing having a substantially cylindrical horizontally disposed interior 7, said valve having a cut-away portion 9 and provided with an enlarged head 10 situated exteriorly of the casing 5, said head being provided with an outwardly extending pin 11 adapted to engage the pin 12 extending outwardly from such casing.

45 13 is a downwardly extending vent communicating at its top with the interior of the valve casing and at its bottom with the interior of the hollow screw plug 6. 14 is a horizontally disposed vent communicating at its inner and with the interior of the casing 5. 15 is a mixer provided with a central orifice 16 into which is inserted a 55 suitable cone-shaped member 17, said mixer

15 being inserted between the carburetor 2 and the intake manifold 1. 18 is a pipe communicating at its top with the vent 14 in the valve casing and at its lower end, through the vent 19, with the hollow interior 16 of the mixer.

20 is a lever secured to the free end of the valve spindle 8. 21 is a rod pivotally connected at one end to the lever 20 and the other end having a turned over portion 22 65 adapted to be inserted into a slot 23 in the member 24, said member 24 having a hook-shaped lower end 25 adapted to freely extend around the rod 21. The member 24 is suitably secured to the spark lever rod 27, 70 and 28 is a spring secured at one end to the upper end of the member 24 and at the lower end to the upper end of the rod 21.

When the engine is started the spark is usually retarded, and when the spark lever 75 is turned into the retarded position the spark lever rod 27 will be turned through the medium of the rod 21 and the lever 20, the valve spindle 8 will be turned so that the cut-away portion will be clear of the 80 vents 13 and 14 thus closing the valve. When the spark lever is advanced the lever 24 will push on the rod 21, and thus through the medium of the lever 20 turn the valve 8 so that the cut-away portion will establish 85 communication between the vents 13 and 14.

When this occurs the air from the stove 4 will pass up through the hollow screw plug 6, through the vent 13, cut-away portion 9, vent 14, through the pipe 18 into the 90 mixer 17 and from thence through into the manifold where it will supply additional or auxiliary air to the mixture.

The pin 12 engaging the pin 11 on the head 10 of the valve will limit the turning 95 of such valve.

The connection shown in Figure 2 between the rod 21 and the lever 24 is to provide a flexible connection rod so that should the spark lever be advanced or retarded too much it will afford a flexible connection between the rod 21 and the lever 24 and thus prevent any damage being done thereto.

From the above description it will be seen that I have devised a simple and effective 105 gasoline saver which can be readily applied to an engine, and in which the control of the admission of auxiliary air into the intake manifold is controlled by the advancing or retarding of the spark lever.

What I claim as my invention is:

An auxiliary air inlet for internal combustion engines comprising a central orificed plate secured between the carburetor outlet flange and the lower intake manifold flange, an imperforate hollow conical member inserted into the orifice in the plate with its smaller end directed towards the intake

manifold, said plate having an auxiliary air inlet extending transversely therethrough and opening into the central orifice intermediate of the length of the truncated conical member, said inlet disposed substantially tangentially to the central orifice. 10

FREDERICK WILLIAM ROMERIL.
